(57) **CLAIM**

We claim the ornamental design for a reconfigurable tiled apparatus, as shown and described.

DESCRIPTION

FIG. 1 is a front perspective view of a reconfigurable tiled apparatus showing the claimed design.

FIG. 2 is a front perspective view showing the pattern of the reconfigurable tiled apparatus;

FIG. 3 is a rear perspective view thereof;

FIG. 4 is a side view thereof; and,

FIG. 5 is a top view thereof.

The broken lines shown in these figures are for illustrative purposes only and form no part of the claimed design.
